Inventor
ROBERT SCHMIDT,

By Richard Oliver.

Attorneys

UNITED STATES PATENT OFFICE.

ROBERT SCHMIDT, OF BOSTON, MASSACHUSETTS.

CHAIR.

Application filed December 31, 1921. Serial No. 526,169.

To all whom it may concern:

Be it known that I, ROBERT SCHMIDT, a citizen of the United States, residing at Boston, in the county of Suffolk and State 5 of Massachusetts, have invented certain new and useful Improvements in a Chair, of which the following is a specification.

The present invention relates to a chair and has for its principal object to provide 10 a device of this nature which is constructed so that it may be readily interchanged from an ordinary chair to a high chair for younger children.

Another important object of the invention 15 is to provide a structure whereby the mechanism forming the high chair may be folded so as to assume a compact position and be placed from sight when not in use.

A still further object of the invention is 20 to provide a chair of this nature which is extremely simple in construction, efficient in operation, economical to manufacture, and well adapted to the purpose for which it is designed.

25 With these and numerous other objects in view as will appear as the description progresses, the invention relates to certain novel features of construction and the combination and arrangement of parts as will 30 be hereinafter more fully described and claimed.

In the drawing:—

Figure 1 is a perspective view of the chair 35 embodying my invention showing the same positioned so as to be used as an ordinary chair,

Figure 2 is a vertical section through the chair showing the main seat in raised position,

40 Figure 3 is a similar view showing the main seat in a closed position,

Figure 4 is a side elevation showing the parts in position so that the chair may be used as a high chair,

45 Figure 5 is a top plan of the structure disclosed in Figure 4,

Figure 6 is a detailed perspective view of the auxiliary seat and a closure,

50 Figure 7 is a detailed section through the auxiliary seat showing a receptacle attached thereto, and

Figure 8 is a detailed perspective view of one arm of the table.

Referring to the drawing in detail it will 55 be seen that the legs of the chair 1 are

preferably four in number and the two rear legs extend upwardly so as to form the supports 2 for the back-rest indicated generally at 3. The front legs 1 extend upwardly so as to form the supports 4 for the arm rests 5 which are attached at their rear ends 60 intermediately to the supports 2. These parts of the chair are conventional and may be of any preferred construction. A box 7 is mounted on the legs 1 and is open at its upper end so as to be normally closed by the main seat 8 which is hinged at 9. A pair of spaced parallel ledges or brackets 10 are mounted on the under-face of the main seat 8. A pair of rods 11 are pivotally mounted to 65 the brackets 10 adjacent the free or forward end thereof and an auxiliary seat 12 is pivoted to the brackets 10 adjacent the pivotal end of the main seat 8. A pair of supporting rods 13 are pivotally attached at one end 70 to the free ends of the rods 11 and intermediate their ends to the ends of the seat 12. A pair of brace rods 14 are pivotally attached to the brackets 10 adjacent the pivotal point of the seat 12. The free ends of 75 the brace rods 14 are slotted longitudinally as at 15 so as to receive pins carried by the supporting rods 13 adjacent their lower ends. When the rods 11, seat 12, supports 13 and brace rods 14 are in the position 80 shown in Figure 4 it will be seen that a high 85 chair is formed.

By raising the seat 12 to the position as shown in Figure 2 it will be seen that the main seat 8 is ready to be fulcrumed to a horizontal position as disclosed in Figure 3 so that the parts just described in conjunction with the high chair may be housed in the box 7 out of the way and out of sight. Particular attention is called to the construction of the auxiliary high chair seat 12 as shown to advantage in Figures 6 and 7, whereby it will be seen that a centrally located opening preferably of elliptical formation is provided at 13 and a cover 17 is provided for this opening 16 and is constructed so as to fit flush therewith because of the annular recess shown at 18 in Figure 7. A pair of brackets 19 are provided on the under-face of the auxiliary seat 12 so that a receptacle 20 may be supported therebetween in alignment with the opening 16. 95

In order to form a table for the high chair I have provided a shelf 22 which when in use is adapted to be situated and sup- 100 105 110

ported on the forward ends of the arm rests 5 as is shown in Figures 2, 4 and 5 and when not in use is adapted to be situated either as shown in Figure 1 or in Figure 3. This 5 shelf 22 is fixed to the supporting arms 23 which are longitudinally slotted adjacent their ends as shown at 24, said slot having an offset portion at 25 closest to the ends of the rods. A projection 27 is formed on the 10 end of each rod 23 for engagement with the stops 28 carried on the supports 2 adjacent the box 7 thus holding the shelf 22 in a position adjacent the upper portion of the back rest 3 and so as to form a part thereof. 15 When it is desired, however, to use the shelf as a table it is lifted so as to free the projections 27 from the stops 28 at which time it may be moved so as to rest on the forward ends of the arm rests 5 at which time the 20 offset portions 25 of each slot 24 will be in engagement with the pins 29 carried intermediate the ends of the supports 2. It will also be seen that this shelf may be lifted clear of the back rest 3 and is pivoted to the 25 rear thereof so as to hang in a position as shown in Figure 3.

The modification of the chair disclosed in the accompanying drawings and described in detail above, refers to the preferred form 30 of the invention and is given only by way of illustration, it being understood that numerous changes in form, material, and in the combination and arrangement of parts may be resorted to without departing from 35 the spirit of the invention as hereinafter claimed.

Having thus described my invention what I claim as new is:—

1. In combination, a chair including a 40 box formed with a bottom and side portions and a hingedly mounted top for forming a

seat and closure for the box, a high chair mechanism including an auxiliary seat pivotally mounted on the first mentioned seat adjacent its hinged end, a pair of rods 45 mounted on the first mentioned seat adjacent its free end, a plurality of supporting rods pivotally mounted to the ends of the first mentioned rods and to the ends of the auxiliary seat intermediate their ends, the ends of said supporting rods adapted to be rested on the bottom of said box when the auxiliary seat is in an operative position, bolts on the supporting rods, and brace rods provided with elongated slots for engaging 50 the bolts and pivotally mounted at their ends adjacent the hinged end of the first mentioned seat.

2. In combination, a plurality of legs, a box supported on the legs, a seat pivotally mounted on the box so as to form a closure therefor, a high chair mechanism including an auxiliary seat pivotally mounted on the first mentioned seat adjacent its fulcrum end, a pair of rods pivotally mounted on the first mentioned seat adjacent its free end, a plurality of supporting rods pivotally mounted to the ends of the first mentioned rods and to the end of the auxiliary seat intermediate their ends, bolts on the 60 supporting rods, and brace rods provided with elongated slots for engaging the bolts and pivotally mounted at their ends adjacent the fulcrum end of the first mentioned seat.

In testimony whereof I affix my signature in presence of two witnesses.

ROBERT SCHMIDT.

Witnesses:

HENRY C. ROCHEFORT,
Mrs. CATHERINE MAHONEY.
